UNITED STATES PATENT OFFICE

2,558,621

COIL WINDING DEVICE

Frank H. Martilla, Minneapolis, Minn.

Application April 5, 1948, Serial No. 19,009

1 Claim. (Cl. 140—92.2)

1

My invention relates to coil-winding devices and, more particularly, to adjustable coil-winding mandrels for use in winding field coils for electric motors and the like.

The primary object of my device is the provision of a structure of the type above-described, upon which concentric coils of substantially the same thickness but of varying circumference may be efficiently and quickly produced.

Another object of my invention is the provision of a device which may be readily adjusted to vary the diametrical or circumferential measurements of the several coils wound thereon.

A still further object of my invention is the provision of a device of the type described having thereon adjustable mandrel elements divided longitudinally into a plurality of mandrel sections which differ in peripheral measurements in a rising series of steps from the ends of the elements toward the centers thereof, whereby to produce two complete sets of coils adapted to be nested in concentric relation.

A still further object of my invention is the provision of a device of the class described which is inexpensive to produce, rugged in construction, and simple to operate.

The above and still further objects of my invention will become apparent from the following detailed specification, appended claim, and attached drawings.

Referring to the drawings, wherein like characters indicate like parts throughout the several views:

Fig. 1 is a plan of my coil-winding device, some parts being broken away and some parts being shown in section;

Fig. 2 is a view in side elevation;

Fig. 3 is a view, partly in end elevation and partly in section, taken on the line 3—3 of Fig. 1; and

Fig. 4 is a view in end elevation seen looking from the right to the left with respect to Fig. 1.

Referring with greater particularity to the drawings, the numeral 1 indicates a head, preferably formed from steel or like material and shown as being in the nature of an elongated bar. Projecting axially outwardly from the central portion of the head 1 is a socket 2 adapted to receive therein the end of a rotary spindle 3 which may be locked therein by means of a set screw or the like 4. The rotary spindle 3 may be attached to a lathe or other means for rotating the same, not shown. On its face opposite the socket 2, the head 1 is provided with a longitudinally-extended outwardly-opening dove

2

tailed guideway 5, the center of which intersects the axis of rotation of the head 1. A pair of tongue-shaped slides 6 and 7 are slidably mounted in the guideway 5. Each of the slides 6 and 7 are provided with legs 8 which project through aligned diametrically-opposed slots 9 in the head 1 and have their free outer ends internally threaded, one with a right-hand thread and the other with a left-hand thread to receive opposite threaded ends of a reversely threaded stud or screw 10. The screw 10 is journalled intermediate its ends in the base portion of the socket 2 and is maintained against axial movements therein by means of stop collars 11. It will be noted that the legs 8 may be formed integrally with the slides 6 and 7 but preferably and as shown are rigidly secured thereto by means of machine screws or the like 12. One end of the screw 10 is provided with a rectangular shank 13 to which a key or wrench may be applied for turning the same.

Secured to the slides 6 and 7 and projecting axially outwardly of the head 1 in opposite directions from the legs 8 are elongated supporting arms 14 and 15 respectively, which preferably and as shown are angular in cross section. The arms 14 and 15 are diametrically-opposed with respect to the axis of rotation of said head and extend outwardly therefrom in parallel relationship.

As shown, a plurality of pairs of matched cooperating mandrel elements 16 are slidably mounted on each of said arms. Adjacent the head, the mandrel elements 16 abut against shoulders 17 on the arms 14 and 15 respectively. A clamp comprises a pair of parallel bars 18; and a cooperating central clamping screw 19 applied to the outer end portions of the arms 14 and 15 both limits the axially outward movements of the mandrel elements 16 and at the same time maintains the parallelism of the free ends of the arms 15 and 16. The mandrel elements 16 are provided with a plurality of radially-projecting fins or partitions 20 which divide said elements into mandrel sections 21 which differ in peripheral dimensions in a rising series of steps A, B, and C from the opposite ends of the elements 16 toward the centers thereof.

With reference to Figs. 2 and 4, it will be seen that each of the fins or partitions 20 is provided with a radially outwardly-opening notch 22, all of which notches 22, as shown in Fig. 2, lie in the same longitudinal plane. As shown in Fig. 1, one of the fins adjacent the abutting ends of the mandrel element 16 is elongated, as indicated at

23, for a purpose which will hereinafter become apparent.

As shown in Fig. 1, the head 1 is provided with a linear scale 24 which extends radially outwardly from the center of rotation thereof along one side edge thereof. Adapted to cooperate with linear scale 24 is an indicating finger 25, which is rigidly secured to one of the arms (shown as being arm 14).

When it is desired to utilize my novel structure, the adjustment stud 10 is turned to properly space the arms 14 and 15 and the cooperating mandrel elements 16 carried thereby to produce a series of coils of the desired diametrical or circumferential measurements. Thereafter, the clamping bars 18 are applied to the outer end portions of the arms 14 and 15 and the clamping screw tightened to rigidly maintain the free ends of the arms in a parallel relationship during the winding of wire upon the mandrels 16. The head 1 is rotatively mounted to the rotary spindle 3, as indicated in Fig. 1. Wire to be coiled on the mandrel elements 16 may be started at either of the opposite ends thereof in one of the steps A. When the desired number of turns has been wound on the step A, rotation of the spindle is stopped or at least slowed down sufficiently to allow the wire to be passed through the notch 22 leading to the adjacent step B and thereafter rotation is started or sped up as the case may be and the required number of turns wound thereon. Similarly, wire is passed through the notch 22 in the fin 20 between the step B and C and the process repeated until all of the mandrel sections on one of the pairs of mandrel elements 16 receive the desired number of turns of wire. Thereafter, the wire is passed through the notch 22 in the elongated fin 23 and the process repeated for the next pair of mandrel elements. When the two pairs of mandrel elements have received the required number of turns of wire, rotation of the device is stopped, the coils are properly tied, the clamping bars 18 loosened from the outer ends of the arms 14 and 15, and the elements 16 slidably removed therefrom. The elements 16 may be easily removed from the arms 14 and 15 if the adjustment screw 10 is rotated in a direction to bring the arms 14 and 15 toward one another. When the wire-covered mandrel elements 16 have been slidably removed from the arms 14 and 15, they may readily be moved toward one another, so as to permit their removal from the coils, thus leaving the coils of wire intact and ready for mounting in the stator of an alternating current motor. The arrangement illustrated provides a set of stator coils for a four-pole alternating current motor. The coils of wire are applied to the stator of the motor in a well-known manner with coils wound on adjacent steps A, B, and C forming concentric coil elements in the stator. The added length of wire caused by the elongated fin or partition 23 between two of the sets of coils allows for the greater spacing between the smaller coils when installed in a motor stator.

The linear scale 24 and the cooperating indicating finger 25 simplify the setting of the arms

14 and 15, whereby to provide an accurate interior periphery for the coils without the necessity of calipers or other measuring devices to ascertain such measurements.

5 When it is desired to wind a connected series of coils as above described for other than a four-pole motor, sufficient pairs of mandrel elements are mounted on the arms 14 and 15 to provide the required number of coils. Hence, when it is desired to wind coils for a two-pole motor, it is only necessary to use but one pair of elements 16. On the other hand, when winding coils for a six-pole motor, three pairs of mandrel elements 16 are necessary.

10 My invention has been found particularly advantageous, not only in the building of new motors, but in the rebuilding of worn-out motors, and has resulted in a substantial saving of time and effort in the winding of field coils therefor; and while I have disclosed a preferred embodiment of my invention as required by section 4888 of the United States statutes, it will be understood that the same is capable of various modifications without departure from the spirit and 15 scope of the invention as defined in the claim.

What I claim is:

In a device of the class described, a rotary head, a pair of diametrically-opposed elongated supporting arms carried by said head and projecting axially therefrom in parallel relationship, screw means on said head for simultaneously moving said arms toward and away from each other, a pair of matching mandrel elements mounted one each on said arms and slidably removable from the free ends of said arms, means limiting movements of said mandrel elements on said arms axially of said head, said mandrel elements being divided longitudinally into a plurality of mandrel sections, said sections differing in peripheral dimensions in a rising series of steps from the ends of said sections toward the centers thereof, and a radially-extended fin between each of said steps and at the opposite ends of each of said elements, said fins being provided with outwardly-opening wire-receiving notches, one of the fins adjacent the abutting small ends of said mandrel sections extending radially outwardly a greater distance than any of the other of said fins.

FRANK H. MARTILLA.
